DECODING GAME APPARATUS

Muriel M. Wiebe, 601 S. Calumet Road, Chesterton, Ind.
Filed May 7, 1958. Ser. No. 733,647
3 Claims. (Cl. 273—130)

This invention relates generally to a game, and more specifically to a decoding game including its accessories.

Although the principles of the present invention may be included in various games, a particularly useful application is made when the principles are included in a game which includes a game board that is provided with a set of playing pieces, together with other accessories.

The present game may be played by a variable number of players, for example two to four, all of which are provided with a coded statement. The object of the game is to decode the statement, and a player scores points for his ability to correctly decode the statement presented. Playing pieces are provided to be arranged in the form of the coded statement and others are substituted therefor to represent the decoded statement during the course of play. Provision is also made to provide the players with clues which partially correctly decode portions of the coded statement, should the players require such assistance. Means are also provided to assist in the scoring and for the display of playing pieces not then in active use.

Accordingly, it is an object of the instant invention to provide a decoding game.

It is a further object of the instant invention to provide a novel set of playing pieces which may be used in a word game.

A still further object of the instant invention is to provide a game accessory member whereby a coded statement and clues for its decoding are included.

Yet another object of the instant invention is to provide a novel method for the playing of a word game.

Many other advantages, features and additional objects of the present invention will become manifest to those versed in the art upon making reference to the detailed description and the accompanying sheets of drawings in which a preferred structural embodiment incorporating the principles of the present invention is shown by way of illustrative example.

In the drawings:

FIGURE 1 is a top view of a decoding game provided in accordance with the principles of the present invention, the playing pieces being omitted;

FIGURE 2 is an enlarged fragmentary view of a portion of FIGURE 1;

FIGURE 3 is an enlarged fragmentary view of a portion of FIGURE 1 with the playing piece tray removed;

FIGURE 4 is a further enlarged view of the structure of FIGURE 3, with a portion thereof removed to reveal indicia thereon;

FIGURE 5 is a front and rear perspective view of a representative playing piece comprising a part of this invention;

FIGURE 6 is an enlarged sectional view taken along line VI—VI of FIGURE 1; and

FIGURE 7 is a perspective view of various scoring bars.

As shown in the drawings:

The principles of this invention are particularly useful when embodied in a decoding game assembly such as illustrated in FIGURE 1, generally indicated by the numeral 10. The game assembly includes a playing board 11, an accessory member 12 normally supported on the board 11, a playing piece tray 13 normally supported on the accessory member 12, a set of playing pieces of which the piece 14 shown in FIGURE 5 is representative, and

2

a plurality of scoring underliner bars of which the bars 15—17 of FIGURE 7 are representative.

The board 11 includes line-type of indicia 18 to set off a plurality of player's zones 19 and a central zone 20.

5 Each of the player's zones 19 includes further indicia which defines a series of aligned playing piece spaces 21, the instant zone 19 as shown in FIGURE 2 having three such series. For convenience, the individual series may be designated in any convenient manner, such as by numbers, and each of the spaces of a series may be individually designated as by the numerals shown thereon. The number of spaces and the number of series provided for each player is not critical per se, a total of 72 spaces usually being adequate.

15 A player's zone 19 is provided for each of the players. The central zone 20 of FIGURE 1 receives and supports the accessory member 12.

20 The accessory member 12 may be, and in this embodiment is, a reduced scale representation of the game board 11. However, in the portion corresponding to the player's zone 19 of the game board, there is provided a zone 22 having indicia arranged in groups which display a coded statement. These indicia are arranged on a series of aligned spaces corresponding in configuration to the series of aligned playing piece spaces 21 of the game board 11.

25 In FIGURE 3, there is shown an enlarged representation of the zone 22, and wherein representative indicia display a coded statement.

30 In FIGURE 3, it will be noted that the number of spaces corresponds to the number of playing piece spaces of FIGURE 2. In this manner, the indicia displaying the coded statement are provided for each player, whereby each can continually view the coded statement.

35 Referring to FIGURE 4, the zone 22 of FIGURE 3 is shown still further enlarged. It will be noted that the identification of each of the series 21 from the game board may be reproduced on the accessory member 12, in this instance such being the numerals 1, 2, and 3. It be further noted that the spaces on the accessory member 12 which do not have indicia which represent a coded statement may be provided with numerals which correspond to the numerals or other indicia carried by each of the playing piece spaces 21 of the board 11. Thus these serve to identify the spaces which do not have any indicia of coded statement, which may be termed blanks.

40 The accessory member 12 has a central clue or decoding zone 23 which may correspond geometrically to the central zone 20 of the game board 11. In the clue zone 23, one or more clues to the decoding of the statement are provided by indicia suitably arranged, which may provide a partial or full decoding of the statement. In this example, it is seen that the letter B in the coded statement has been used for the letter R in the decoded statement. Similarly, the letter Q stands for the letter C, and the letter T stands for the letter S. Preferably, the member 12 also includes indicia which completely and correctly decode the coded statement. In order that only one of the clues in the clue zone may be revealed at a time, means 24, such as a removable or liftable tab, 45 are provided to cover each of the sets of indicia which provide clues. This is best seen in FIGURE 3. Upon lifting of the tab means 24, the indicia are revealed as shown in FIGURE 4. In FIGURE 1, the playing piece tray 13 is shown as disposed upon and resting on the clue zone 23 of the accessory member 12, and therefore applying a force to the several tabs 24 to hold them in place and to minimize the opportunity for premature exposure of the indicia therebeneath.

45 Referring to FIGURES 1 and 6, the playing piece tray 70 includes a stand 30 having a pivot pin 31 secured thereto and extending upwardly therefrom. The tray 13 further includes a double bottomed member having a lower bot-

tom 32 which is apertured to receive the pin 31 and to rest on a spacer 33. If desired, a reinforcing member 34 suitably apertured to receive the pin 31 may also be included as shown. The upper bottom member 35 is provided with a series of alternately directed creases whereby portions thereof are angularly directed, as at 36 and 37. The upper bottom 35 is provided with slits which extend from the point 38 to the points 39 for each of the similarly situated alternate creases. A divider 40 is received within the aligned slits. As best seen in FIGURE 1, several dividers 40, in this instance 6, are contained in the tray 13 whereby a total of 28 compartments or articulations are provided for receiving individual playing pieces 14. A side member 41 is also included at each of the sides of the tray 13. Thus the tray 13 is rotatably supported, is compartmented, and has an angularly directed bottom in each of the compartments.

The playing pieces 14 also form a part of the game 10. The pieces may be made in any convenient form, such as of composition board, plastic, heavy paper, and the like and are each provided with indicia which represent the various individual letters of the alphabet. Preferably, each of the playing pieces 14 is so dimensioned that it has the same size as the playing piece spaces 21 of the game board 11, and as the angularly directed bottom 37 of the playing piece tray 13.

At the start of the game, each of the players is provided with a coded statement; in this case the indicia at the zone 22 of the member 12 do this. Of course, the coded statement may be provided in any one of various ways. Preferably each player selects playing pieces 14 to set up or duplicate the coded statement on his own zone 19, remotely from the accessory member 12, the numbered playing piece spaces on FIGURE 4 representing the playing piece spaces on FIGURE 2 which are left blank.

The various playing pieces which are not placed on the game board may be placed on the playing piece tray for future use.

Each of the players then studies the indicia representing the coded statement, either on the member 12 or as indicated by the arranged playing pieces 14 to determine what substitutions he can make. These are made based upon his own ability to reason. For example, a single letter word is obviously the letter A or I. The letter which follows an apostrophe is likely to be the letter S or T. Double letters also serve as clues, particularly in conjunction with other known letters.

The play continues in turn in accordance with such rules of play as may be established. As a statement is decoded, the playing pieces which are decoded are returned to the playing piece tray, and others selected therefrom to take their place on the playing piece spaces 21.

From time to time, players will be able to proceed no further. At such points, and under such conditions as the rules may establish, the tray 13 may be moved so that one of the tabs 24 can be removed or lifted so as to expose at will the clue indicia thereunder. The players being provided with this additional information continue to play in accordance with the rules.

To score the game, credit may be given to the player who first correctly decodes a word, group of words, or the entire statement. Penalties may be imposed for mistakes. Progressively less credit may be awarded a player for correct decoding as an increasing number of clues have been exposed. The credit for a correctly decoded word may also be weighted for the size of the word.

Obviously, each player will be able to observe what the other player is doing, and will be able to adopt his word arrangement if he so desires. To simplify record keeping and scoring, I have provided the scoring bars, such as 15-17 of FIGURE 7 for indicating groups of indicia which have been decoded, and which may be

disposed adjacent to the playing pieces of a player who is entitled to a premium score, such as due a player who first suggests the correct decoding or translation. Thus, the scoring bars preferably have a length which is equal to a multiple of the width of the playing pieces 14.

Of course, various colors of bars or playing pieces may be utilized as a further aid in scoring.

It is apparent that the set of playing pieces 14 must include a relatively large number of playing pieces which severally have indicia representing each of the individual alphabet letters thereon. It is also apparent that more playing pieces will be needed with certain indicia than with others, particularly the vowels. In order not to excessively duplicate the number of playing pieces needed, I have provided indicia on both sides of the playing piece, such as shown in FIGURE 5. However, during the use of the playing pieces 14, it is desirable to know the letter which is on the reverse side of the piece without turning it over. Therefore, for most of the playing pieces and including all of the consonants, the letter which has been provided on the reverse or other side represents the next alphabetically succeeding letter. In this way, a player may view a playing piece and know that the letter on the other side is always the next succeeding or preceding letter in the alphabet. For example if a player sees the letter N he knows that the letter on the other side is either M or O. For this purpose, the letter A is considered to precede the letter B and to follow the letter Z.

While certain of the playing pieces have been provided with indicia indicating letters as described, additional playing pieces have been provided which duplicate the vowel letters. On the reverse side of these additional vowel playing pieces, I have provided indicia which represent punctuation marks.

The following table represents a distribution of playing pieces which I have found to be ordinarily adequate:

	Pieces
40 A and B	6
B and C	4
C and D	4
D and E	6
E and F	4
45 F and G	4
G and H	4
H and I	6
I and J	4
J and K	4
50 K and L	4
L and M	12
M and N	4
N and O	10
O and P	6
55 P and Q	4
Q and R	4
R and S	10
S and T	10
T and U	10
60 U and V	4
V and W	6
W and X	6
X and Y	4
Y and Z	4
65 Z and A	4
A and .	4
A and '	4
A and ,	4
E and -	4
70 E and ?	4
E and !	4
I and ;	4
I and -	4
I and .	4
75 O and ,	4

Insofar as the scoring underliner bars are concerned, I have found that it is unnecessary to provide bars having a length representing an odd multiple of the width of a playing piece 14. This is so because there is no harm if a blank space adjacent to a word is underlined. Thus, I have found that eight underliner bars 17 for two playing pieces, eight underliner bars 16 for four playing pieces, and six underliner bars 15 for six playing pieces suffices.

It is to be understood that the accessory member 12 may be provided with a second coded statement zone 22 and a second clue zone 23 on its reverse side. It is also to be understood that a number of accessory members 12 may be provided for each game assembly, and that such accessory members may be separately provided and made available to the possessors of such game assemblies. 10 15

Although various minor modifications might be suggested by those versed in the art, it should be understood that I wish to embody within the scope of the patent warranted hereon all such embodiments as reasonably and properly come within the scope of my contribution 20 to the art.

I claim as my invention:

1. A decoding game for a number of players including in combination: a first member having fixedly-carried first indicia arranged in groups openly displaying at least one coded statement; said first member having additional indicia arranged directly thereon remotely from said first indicia to provide at least a partial decoding of said first indicia; a selectively liftable member secured to said first member for continual use and normally covering said additional indicia to keep them normally unexposed to view; a playing-piece tray having a base normally supported by said liftable member and applying a force thereagainst to ensure that said additional indicia remain unexposed to view; a set of playing pieces severally supported by said tray, and each of a size somewhat larger than said first indicia, which pieces are severally provided with corresponding indicia of somewhat larger size than said first indicia, and a number of which may be freely arranged only remotely from said first indicia, without obscuring the same to reproduce said groups of first indicia, said playing pieces being individually rearrangeable at will; and a set of identifying and scoring underliner bars having lengths substantially corresponding to the lengths of said groups of indicia and which 30 35 40 45

bars are adapted to be severally disposed adjacent to selected groups of said set of playing pieces.

2. A decoding game for a number of players, comprising:

- (a) a member;
- (b) first indicia fixedly carried on said member and disposed in several closely arranged groups openly and jointly comprising and displaying a coded puzzle;
- (c) a set of rectangular playing pieces of a uniform width, each of which is somewhat larger than said first indicia, which playing pieces are severally provided with corresponding indicia of somewhat larger size than said first indicia, said pieces being individually freely arrangeable in straight laterally abutting elongated groups, only remotely from said first indicia without obscuring said first indicia, for reproducing said groups of first indicia; and
- (d) a set of scoring and identifying bars of uniform transverse cross-section and of various lengths, each of said bars having a length which is longer than and which is also substantially an integral multiple of said playing-piece width, whereby said bars may severally be disposed adjacent to and coextensively with all the playing pieces of selected groups of said playing pieces.

3. A game as claimed in claim 2 where all the lengths of said bars are even multiples of said playing-piece width.
